UNITED STATES PATENT OFFICE.

HAROLD DONALD WELLS, OF GLENS FALLS, NEW YORK.

SCREENING OR FILTERING APPARATUS.

1,346,690.

Specification of Letters Patent. Patented July 13, 1920.

Application filed September 18, 1919. Serial No. 324,429.

To all whom it may concern:

Be it known that I, HAROLD DONALD WELLS, a citizen of the United States, and a resident of Glens Falls, in the county of Warren and State of New York, have invented a new and Improved Screening or Filtering Apparatus, of which the following is a full, clear, and exact description.

The invention relates to the manufacture of paper and its object is to provide a new and improved screening or filtering apparatus designed for use as a pulp thickener or as a pulp washer or as a water filter.

Another object is to provide an apparatus of the type referred to which has a large capacity, requires little or no labor attendants, avoids loss of pulp, and reduces the cost of power, wear, labor and repairs to a minimum.

Another object is to provide an apparatus of simple and durable construction and one that is not liable to get easily out of order.

With these and other objects in view, the invention consists of certain novel features of construction, as hereinafter shown and described and then specifically pointed out in the claims.

A practical embodiment of the invention is represented in the accompanying drawings forming a part of this specification, in which similar characters of reference indicate corresponding parts in all the views.

Figure 1 is a plan view of the improved screening or filtering apparatus;

Fig. 2 is a side elevation of the same with the eccentric shaft shown in section;

Fig. 3 is a longitudinal central section of the same on the line 3-3 of Fig. 1;

Fig. 4 is a cross section of the same on the line 4-4 of Fig. 3;

Fig. 5 is a plan view of the eccentric shaft; and

Fig. 6 is an end elevation of the same.

In the manufacture of pulp for paper, it is often the practice after screening the pulp to remove part of the water therefrom by means of thickeners to facilitate mixing one with the other to make paper. Pulps produced by chemical processes or mixed with chemicals for bleaching, etc., require washing by adding water and then filtering out the chemicals with the water before being made into paper. Also water used in the manufacture of pulp and paper is generally filtered to remove dirt, bark, leaves and other extraneous matter. The appa-

ratus presently described in detail can be used for screening the pulp, to thicken the same, or to wash the pulp and filter out the chemicals, or to filter the water to remove dirt, bark, leaves and other extraneous matter.

On a suitably constructed framework 10 is mounted an inclined box 11 provided between its ends 12 and 13 with spaced transverse partitions 14. Into the open top of the box 11 extends a screen 20 comprising a screen plate 21 mounted on spaced transverse partitions 22 fastened to sides 23 extending above the screen plate 21, as plainly shown in Figs. 3 and 4. The screen 20 is inclined the same as the box 11, and its upper end is provided, with a distributing compartment 25 provided with baffles 26 and 27 for uniformly distributing the material to be screened or filtered onto the upper end of the screen plate 21. Into the compartment 25 extends a discharge spout 30 connected with a supply duct 31 for supplying pulp or other material to be screened or filtered to the compartment 25, the amount of the material being regulated by a suitable gate 32.

The lower end of the box 11 discharges into a discharge compartment 40. The lower end 41 of the screen plate 21 is curved downwardly and delivers the pulp or other material to a receiving compartment 42, both compartment 40 and 42 being attached to the main frame 10.

In order to impart a rising and falling and a longitudinal oscillating motion to the screen 20, the following arrangement is made: On the under side of the head compartment 25 is arranged a bearing 50 engaging an eccentric 51 formed on a shaft 52 journaled in suitable bearings 53 attached to the main frame 10. On one end of the shaft 52 is secured a pulley 54 connected by belt with other machinery for imparting a rotary motion to the shaft 52 to cause the eccentric 51 thereof to impart a longitudinally shaking movement to the screen 20. The lower ends of the sides 23 of the screen 20 are hung on spring bars 55 attached to a crossbar 56 supported by brackets 57 fastened to the sides 58 of the box 11. It will be noticed that by the arrangement described the head end of the screen 20 receives an up and down and longitudinally shaking movement from the eccentric 51 while the lower end of the screen

20 is held suspended from the spring suspension members 55.

By reference to Fig. 3, it will be noticed that the partitions 14 of the box 11 terminate a distance below the screen plate 21 of the screen 20, and the partitions 22 of the screen plate 21 terminate a distance above the bottom of the box 11 but below the tops of the partitions 14 thereby providing suction and pressure compartments underneath the screen plate 21 and which compartments are sealed by the water held in the box 11 to a level corresponding to the tops of the partitions 14. It will be noticed that when the apparatus is in use and paper pulp, for instance, is fed onto the screen plate 21 and the screen 20 rises then air is sucked through the screen plate 21 into the suction compartments, and when the screen 20 descends air is forced out of the suction compartments through the meshes in the screen plate 21. The escaping air slightly lifts the pulp and the forward and backward motion given to the screen shakes the pulp down the inclined screen plate 21 to finally pass into the receiving compartment 42, from which the pulp is conducted to a storage tank or other suitable receptacle. The water sucked from the pulp during the suction operation of the screen passes into the box 11 and over the overflow partitions 14 to finally pass over the end 13 into the compartment 40 from which the waste water is conducted to a sewer or other place of discharge.

When the machine is used as a water filter then the refuse material passes over the screen plate 21 into the compartment 42 while the filtered water passes through the screen plate 21 into the box 11 and finally reaches the compartment 40 to be pumped from the latter to a storage tank or other suitable compartment.

Having thus described my invention, I claim as new and desire to secure by Letters Patent:—

1. In an apparatus of the type described, a box provided with spaced transverse par-

titions, a screen extending into the said box and provided at the under side with spaced transverse partitions extending between the partitions of the said box, the said partitions on the box and screen forming suction and pressure compartments underneath the screen above the box portions, and forming water sealing compartments in the box, and means imparting a rising and falling and a longitudinal oscillating motion to the said screen.

2. In an apparatus of the type described, an inclined box provided with spaced transverse partitions, an inclined screen extending into the said box and provided at the under side with spaced transverse partitions extending between the said box partitions, a receiving compartment at the upper end of the said screen and provided with transverse baffles to spread the material uniformly over the screen, discharge compartments on the lower end of the said box, one for receiving the water from the box and the other the material discharged at the lower end of the screen, and means imparting a rising and falling and a longitudinally oscillating motion to the said screen.

3. In an apparatus of the type described, an inclined box provided with spaced transverse partitions, an inclined screen extending into the said box and provided at the under side with spaced transverse partitions extending between the said box partitions, a receiving compartment at the upper end of the said screen and provided with transverse baffles to spread the material uniformly over the screen, discharge compartments on the lower end of the said box, one for receiving the water from the box and the other the material discharged at the lower end of the screen, a driven eccentric shaft, a bearing attached to the upper end of the said screen and engaging the said eccentric shaft, and a spring suspension device supporting the lower end of the said screen and allowing the latter to swing longitudinally.

HAROLD DONALD WELLS.
